RALPH K. MILLER, OF DAYTON, OHIO, ASSIGNOR TO FRIGIDAIRE CORPORATION, OF DAYTON, OHIO, A CORPORATION OF DELAWARE

REFRIGERATING APPARATUS

Application filed April 25, 1931. Serial No. 532,894.

The present invention relates to refrigerating apparatus and more particularly to refrigerating apparatus of the compression type wherein a lubricant is circulated in a closed cycle with the refrigerant.

Heretofore in refrigerating systems of the compression type trouble has been experienced because oil employed to lubricate operating parts of the system has accumulated on the walls and on top of the liquid refrigerant within the evaporator. This accumulation of oil on the walls and within the evaporator becomes very viscous, as the temperature of the evaporator is reduced, and forms a thick layer or blanket on the refrigerant which hinders or retards evaporation of the liquid refrigerant contained in the evaporator.

The object of the present invention is to provide heat conducting means of high thermal conductivity for conducting heat from the exterior of the evaporator directly to the liquid refrigerant to cause the liquid refrigerant to boil more readily. In carrying out my invention I provide an evaporator with a member of high heat conductivity which extends exteriorly of the evaporator and is subjected to a relatively warm medium and is arranged for conducting heat below the blanket of oil floating on the liquid refrigerant.

Further objects and advantages of the present invention will be apparent from the following description, reference being had to the accompanying drawing, wherein a preferred form of the present invention is clearly shown.

In the drawing:

Fig. 1 is a vertical section through a portion of an evaporator having my invention embodied therein and having a refrigerating system shown diagrammatically adapted to be connected with the evaporator;

Fig. 2 is a vertical section through an ice cream cabinet having an evaporator constructed in accordance with my invention installed therein;

Fig. 3 is a sectional view of the evaporator taken on the lines 3-3 of Fig. 1, and

Fig. 4 is a sectional view of a portion of

the evaporator taken on the lines 4-4 of Fig. 1.

For the purpose of illustrating the present invention I have shown in Fig. 1 a compressor-condenser-expander type of refrigerating system having an evaporator 10 shown in section on a large scale and including connections 11 and 12 for operatively connecting the evaporator with the system. In addition to the evaporator the system includes a compressor 13, a condenser 14 and a reservoir or liquid refrigerant tank 15. Refrigerant vapor is withdrawn from the evaporator 10 through the vapor or low pressure conduit 16 and is liquefied in the condenser 14 and returned to the evaporator through the liquid or high pressure conduit 17. The compressor is operated by a motor 18 controlled by an automatic switch 19 which may be actuated in response to the refrigerating demand, for example by a pressure responsive device 21 connected to the low pressure conduit 16. It is obvious, in systems of the type disclosed, to state that the pressure-responsive device 21 which actuates the switch 19 for controlling the electric circuit to the motor is adjusted to operate between certain pressure limits. Since pressures and temperatures of the refrigerant increase or decrease uniformly it is apparent that the device 21 is adapted to maintain certain predetermined temperature limits within the evaporator of the system.

Referring to Fig. 1, evaporator 10 comprises a header 24 forming a reservoir for liquid refrigerant, and a plurality of ducts 25 depending from the header 24 for circulating refrigerant to a point remote from the reservoir. The liquid refrigerant indicated at 26 is kept at a constant level 27 by a valve 28 which controls a liquid refrigerant inlet opening 29 extending from the connection 11 through an end plate 30. Valve 28 is actuated in response to the liquid refrigerant level by a float 31. The liquid refrigerant is supplied to the evaporator through the inlet connection 11 and the vapor or gaseous refrigerant is withdrawn through the connection 12 connected to the vapor conduit 16.

The apparatus, or system, as generally described above is lubricated by placing a quantity of oil in the crankcase of the compressor and depending upon the splashing of the rotating parts to distribute oil throughout the compressor. Some of the oil is dissolved in the refrigerant and some of the oil is mechanically pumped by the compressor to the condenser and reservoir and eventually to the evaporator. The oil in separating by gravity from the refrigerant in the evaporator forms globules which adhere to the walls thereof and tend to remain stationary. These globules of oil form a layer of insulation between the liquid refrigerant in the evaporator and the wall thereof which insulation retards the conduction of heat from the evaporator wall to refrigerant contained therein and consequently evaporation of the refrigerant is also retarded. Finally after the refrigerant absorbs sufficient heat to cause its evaporation a disturbance occurs in the evaporator and the globules of oil are carried to the top of the liquid refrigerant. The refrigerant continues to boil off in the evaporator, leaving the oil, which collects in a layer of from $\frac{1}{2}$ " to $1\frac{1}{4}$ " thick on the top of the refrigerant. This layer of oil on top of the refrigerant in the evaporator becomes more viscous as the temperature of the evaporator is reduced and forms a heavy blanket on top of the refrigerant, the effect of which must be destroyed before evaporated refrigerant can enter the space above the oil so as to affect the pressure responsive device which controls the starting and stopping of the motor and compressor.

This collection or accumulation of oil in the evaporator is particularly harmful when the system is used to refrigerate an ice cream cabinet or the like, wherein very low temperatures are desired to be maintained. Under such conditions within the evaporator of the system the compressor will be operated frequently and only for short intervals of time, thus causing short operating cycles of the compressor. These "short cycles" of the compressor are caused by the compressor creating a suction in the low pressure conduit 16 and in the space above the liquid level within the header 24 of the evaporator, sufficient to cause the pressure-responsive device 21 to actuate the automatic switch 19 and break the electric circuit to the motor 18, thus stopping the compressor, without breaking up the layer of oil in the evaporator, thereby preventing liquid refrigerant below the layer of oil from vaporizing. Obviously such short cycles of the compressor will continue indefinitely and the evaporator will not be reduced to the temperature at which the pressure responsive device 21 has been set to maintain therein. Consequently the motor which drives the compressor is started an abnormal number of times causing overheat-

ing thereof. Furthermore, the refrigerating efficiency of the evaporator becomes decreased, thereby permitting the temperature within the compartment in which the evaporator is located to increase. This inefficient operation of a system will not maintain substances cooled thereby at the desired temperature and is very likely to permit the substances to deteriorate.

The foregoing mentioned difficulties occur because the walls of evaporators are ordinarily constructed of inexpensive materials, which materials do not conduct heat as rapidly as other materials more desirable but too expensive to warrant their use. It has been found that even if the walls of an evaporator are constructed of good heat conducting material, evaporation of the refrigerant therein is retarded until a large quantity thereof vaporizes and creates a sufficient pressure to break through the heavy viscous layer of oil on top of the refrigerant. Such accumulation of vaporized refrigerant beneath the oil, until a sufficient pressure is created, causes liquid refrigerant to be splashed into the gaseous refrigerant outlet leading from the evaporator when the accumulated pressure finally breaks through the layer of oil. This thereby causes refrigeration outside of the compartment to be refrigerated and renders the system inefficient. Such action of the refrigerant within the evaporator is caused by the large heat absorbing surfaces of the evaporator which distribute the heat throughout the entire body of liquid refrigerant and consequently does not form sufficient pressure at any one point to break through the layer of oil, thereby permitting the temperature of the medium cooled by the evaporator to increase above a desired limit. Thus the evaporator becomes inefficient to maintain a substantially constant low temperature of the medium or substance being cooled.

My invention is directed to a system whereby the heat of the medium cooled by the evaporator of the system is conducted to and concentrated at one point within the liquid refrigerant beneath the layer of oil in the evaporator and consequently the refrigerant and oil is positively agitated sufficiently to cause the blanket or layer of oil to be broken up or to cause its blanketing effect to be destroyed. This thereby permits liquid refrigerant within the evaporator to vaporize and prevents the compressor from reducing the pressure in the space above the layer of oil and in the low pressure conduit to a degree sufficient to effect the pressure responsive device until the desired low temperature of the evaporator has been obtained. I provide a device which utilizes the difference in temperature of the medium to be or being cooled by the evaporator and the temperature of the liquid refrigerant within the evapora-

tor for causing liquid refrigerant to evaporate or break through the oil blanket within the evaporator.

Referring now to Fig. 1, I have provided means to destroy the blanketing effect of lubricant in an evaporator for causing the evaporator to maintain a substantially constant temperature. This means includes a solid bar or member 40 constructed or formed of material of high heat conductivity and capable of transmitting heat rapidly such as pure copper. The bar or member 40 extends through a wall of the header 24 and is sealed to this wall. Member 40 includes an end portion 41 extending inwardly from the wall to a point below the liquid refrigerant within the evaporator. Another end portion 42 of the bar 40 extends outwardly from the wall of the header 24 and has fins or heat absorbing members 43 secured thereto for increasing the heat absorbing capacity of the bar 40. These fins 43 are also made of material of high heat conductivity and are adapted to be spaced from the walls of the evaporator so as to be disposed in the medium being cooled by the evaporator. Owing to the construction of evaporators and the difficulties heretofore pointed out this bar or member 40 being considerably higher in temperature than the liquid refrigerant contained in the evaporator will absorb heat from the medium being cooled by the evaporator more readily than can be accomplished by walls of the evaporator and will rapidly conduct or transmit heat to a concentrated point in the liquid refrigerant beneath the layer of oil in the evaporator and cause its evaporation and consequently agitation of the body of liquid in the evaporator.

Referring now to Fig. 2, I have shown my improved evaporator installed in an ice cream cabinet generally designated as 50. However, I do not wish to be limited to the particular installation shown for illustrating my invention. The construction and arrangement of the ice cream cabinet may be of the type fully described in a copending application of Jesse G. King, Serial No. 86,586, filed February 6, 1926. The cabinet 50 may include insulating side and bottom walls 51 which surround a brine tank 52 containing a medium to be cooled such as a body of brine indicated as 53 for conducting heat from ice cream can receptacles 54 to the evaporator 10. The insulated top wall 55 of the cabinet has openings therein (not shown) to permit access to the receptacles 54 which openings may be closed by covers or lids 56. The evaporator 10 is submerged in the body of brine 53 and the end portion 42 of bar or member 40 extends upwardly from the evaporator to a point near the upper surface of the body of brine, which surface is somewhat warmer than the lower portion of the body of brine due to the thermosyphon circulation thereof.

The bar 40 thus absorbs heat from this relatively warmer portion of the brine and conducts it to the liquid refrigerant contained in the evaporator to cause evaporation thereof. Should the evaporator be very cold and oil therein tend to retard evaporation of refrigerant, whereby the medium being cooled by the evaporator will increase beyond the desired temperature limit, my improved device will rapidly transmit and concentrate the heat caused by such increase of temperature to the refrigerant in the evaporator, thereby causing evaporation thereof to destroy the blanketing effect of lubricant floating thereon which renders the evaporator more efficient to maintain the temperature of the medium to be cooled substantially constant.

While I have shown a preferred form of my improved apparatus, it is thereby understood that certain modifications in construction might be made without departing from the scope of the invention. For example, it may be desirable to make the heat conducting bar or member of rod material having a diameter of considerable greater dimension than the thickness of a wall of the header through which the bar passes so that in case some of the heat being conducted by the bar is dissipated to this wall, the bar will however, be of sufficient thickness to insure conduction of heat through its center portion. Furthermore, it may also be desirable to insulate the bar in any well-known suitable manner from the wall through which it passes to insure that it will be efficient for carrying out the object of my invention.

From the foregoing it is apparent that I have provided an improved apparatus which is sure in its operation and which functions efficiently when the system is operating to maintain a very low temperature, which low temperature increases the viscosity of lubricant, while at the same time providing means for preventing the lubricant from retarding evaporation of liquid refrigerant in the evaporator. My improved apparatus, by destroying the blanketing effect of the lubricant floating on the liquid refrigerant in the evaporator, insures positive and regular circulation of refrigerant through the evaporator and prevents violent intermittent ebullitions of the refrigerant thus preventing liquid refrigerant from being splashed into the gaseous refrigerant outlet of the evaporator. With this accomplished evaporators employed to produce very low temperatures are rendered more efficient for maintaining a constant range of temperature. Likewise the life of the compressor and its operating motor is prolonged by the prevention of the heretofore described short operating cycles thereof.

While the form of embodiment of the invention as herein disclosed constitutes a preferred form, it is to be understood that other forms might be adopted, all coming

within the scope of the claims which follow.

What is claimed is as follows:

1. An evaporator of the type in which a large body of liquid refrigerant is maintained and in which a layer of lubricant floats on the liquid refrigerant, the combination of means for causing agitation of the refrigerant so as to destroy the blanketing effect of the lubricant, said means including an element of high heat conductivity especially constructed for readily conducting heat to a concentrated point in the body of liquid refrigerant and having a part thereof extending outside the evaporator and especially constructed and positioned so that it is exposed to the temperature of the circulating medium to be cooled by the evaporator and maintained at a materially higher temperature than the liquid refrigerant in the evaporator. 5
2. An evaporator of the type including a header in which a large body of liquid refrigerant is maintained and in which a layer of lubricant floats on the liquid refrigerant, the combination of means for causing agitation of the refrigerant so as to destroy the blanketing effect of the lubricant, said means including an element of high heat conductivity especially constructed for readily conducting heat to a concentrated point in the body of liquid refrigerant and having a part thereof extending outside the header and especially constructed and positioned so that it is exposed to the temperature of the circulating medium to be cooled by the evaporator and maintained at a materially higher temperature than the liquid refrigerant in the header. 10
3. An evaporator of a refrigerating system adapted to contain a body of liquid refrigerant and a layer of oil on the refrigerant, said evaporator being positioned in a medium to be cooled thereby, means for conducting heat from said medium to a concentrated point in the liquid refrigerant within said evaporator to agitate the refrigerant and cause the blanketing effect of the oil to be destroyed, said means including a solid member of high heat conductivity having a portion extending outwardly from a wall of said evaporator into said medium and having another portion extending inwardly from a wall of the evaporator and terminating below the liquid refrigerant level in said evaporator, and means on the first mentioned portion of said member for increasing the heat absorbing capacity thereof. 15
4. An evaporator of a refrigerating system adapted to contain a body of liquid refrigerant and a layer of oil on the refrigerant, said evaporator being positioned in a medium to be cooled thereby, means for conducting heat from said medium to a concentrated point in the liquid refrigerant within said evaporator to agitate the refrigerant and cause the blanketing effect of the oil to be destroyed, said means including a solid member of high heat conductivity having a portion extending outwardly from a wall of said evaporator into said medium and having another portion extending inwardly from a wall of the evaporator and terminating below the liquid refrigerant level in said evaporator, and means on the first mentioned portion of said member for increasing the heat absorbing capacity thereof. 20
5. An evaporator of a refrigerating system adapted to contain a body of liquid refrigerant and a layer of oil on the refrigerant, said evaporator being positioned in a medium to be cooled thereby, means for conducting heat from said medium to a concentrated point in the liquid refrigerant within said evaporator to agitate the refrigerant and cause the blanketing effect of the oil to be destroyed, said means including a solid member of high heat conductivity having a portion extending outwardly from a wall of said evaporator into said medium and having another portion extending inwardly from a wall of the evaporator and terminating below the liquid refrigerant level in said evaporator, and a plurality of fins of high heat conductivity on the first mentioned portion of said member for increasing the heat absorbing capacity thereof. 25

In testimony whereof I hereto affix my signature.

RALPH K. MILLER.
